CLAIM

I claim the ornamental design for a peacock novelty, as shown and described herein.

DESCRIPTION

FIG. 1. Is a front view of my peacock novelty;

FIG. 2. Is a rear view thereof;

FIG. 3. Is a right side elevational view thereof with the left side elevational view being a mirror image thereof;

FIG. 4. Is a top view thereof; and,

FIG. 5. Is a bottom view thereof.

The portions shown in broken lines are for illustrative purposes only; and form no part of the claimed design.
